UNITED STATES PATENT OFFICE.

DONALD BARNS MORISON, OF HARTLEPOOL, ENGLAND.

WATER-JET EJECTOR.

1,076,600.

Specification of Letters Patent.

Patented Oct. 21, 1913.

Application filed March 21, 1912. Serial No. 685,264.

To all whom it may concern:

Be it known that I, DONALD BARNS MORISON, a subject of the King of Great Britain and Ireland, residing at Hartlepool, in the 6 county of Durham, England, have invented Improvements in Water-Jet Ejectors, of which the following is a specification.

This invention relates to improvements in water jet ejectors, such for example, as may 10 be used in connection with steam condensing plant working under vacuum.

The principal object of the invention is to obtain a high efficiency from such apparatus when using a given quantity of water and 15 a given amount of power.

In carrying out the invention in one particular form, and for the purpose of withdrawing air from a steam condenser, the apparatus may be constructed in the following manner: Within a receiver into which the mixture of air and vapor passes from the condenser or into which receiver it may be discharged from the condenser by means 20 of a steam jet device, there are arranged multiple jets of water for the condensation of the vapor and the discharge of the air, such jets being divided into groups so that the water from each group converges into a separate combining or collecting tube each 25 30 35 40 45 50 55 60 65 70 75 80 85 90 95 100 105 110

separate combining or collecting tube being arranged with an annular water jet which draws the water and air from the tube and discharges it into a pipe common to all, the lines of flow from the receiver through each combining tube converging into the common discharge pipe.

I have found by careful experiment that the air entraining and withdrawing capacity of a water jet air ejector is largely influenced by the proportions and dispositions adopted, so that in apparatus according to the present invention, facilities are afforded for proportioning and disposing each group or unit to the best advantage for the particular purpose employed, and then by multiplying units in the manner described a very high aggregate efficiency is obtained.

The particular design of apparatus according to the present invention may vary 50 in accordance with the requirements, for example, in the apparatus just described, the annular or other jets, may, instead of delivering into one common discharge pipe, discharge independently of each other. Or 55 there may be main jets or multiple smaller

jets, or both, arranged in groups in the receiver, each group discharging into a combining tube leading into a common discharge pipe, and beyond the point of convergence of the several combining tubes 60 there may be an annular jet common to all such tubes.

In the accompanying illustrative drawings, Figures 1, 3, 4 and 6 show in sectional elevation various constructions of water jet 65 ejectors according to my invention, it being understood that the upper part of Figs. 1 and 4 are shown broken away from the lower part, and Figs. 2 and 5 underside views respectively of the portions *a* of the 70 water jet ejectors shown in Figs. 1 and 4.

In all the figures the same letters of reference are used to denote the similar parts.

Referring to Figs. 1 and 2, the water jet 75 ejector comprises a casing built up of three sections *a*, *b* and *c*, Fig. 2 being an underside view of the section *a* which is shown in sectional elevation in Fig. 1. The upper portion *a* forms with the portion *b* a receiver *h* and contains a water supply chamber *d* 80 having three extensions *e* which are provided with central water jet nozzles *f* and multiple smaller nozzles *g* discharging into the combining tubes *h* contained in the middle section *b* of the apparatus. The tubes 85 *h* are provided with adjustable nozzles *l* so as to form with the lower section *c* the annular jets *m* which deliver from the chamber *p* into the common discharge pipe *n*. The nozzles *l* may be screwed into the combining tubes *h* in the manner illustrated and fitted with lock nuts *o* so that by adjusting the nozzles in or out of the combining tubes the amount of water passing through the annular jets *m* may be varied. The water is 90 supplied to the chamber *d* through the branch *r* and into the chamber *p* through the branch *s*, the branches being connected to the same or independent means of supply and may be provided with valves so that the 95 supply of water to the ejector can be regulated.

The water jet ejector described may be connected by the pipes *t* and *t'* to a steam jet device *t''* which is adapted for use in connection with steam engine condensers working under vacuum, the air and vapor being withdrawn from the condenser through the inlet *j* and discharged by the steam jet *x* through the pipes *t'* *t* into the receiver *h* 100 105 110

wherein the steam is condensed and the air discharged from the receiver by the water jets.

Fig. 3 is a modification of the arrangement shown in Fig. 1 and in which the combining tubes *k*, instead of being provided with independent annular jets *m*, Fig. 1, are arranged with a common annular jet *m'* in advance of the point of convergence of the combining tubes *k*.

Figs. 4 and 5 illustrate another construction of water jet ejector according to my invention, Fig. 5 being an underside view of the section *a* which is shown in sectional elevation in Fig. 4. The apparatus is similar to that shown in Figs. 1 and 2, except that the ejector contains six groups of jets, each group consisting of a central solid water jet *f*, multiple smaller jets *g*, and arranged in advance thereof the annular jets *m*, the whole of the jets receiving their supply of water through the inlet branch *s* which is in direct communication with the chamber *p* and communicates with the chamber *d* through the passage *i*. The lower section *c* forming the discharge pipe *n*, is provided with tubes *n'* which form with the nozzles *l* the annular water jets *m*, the nozzles *l* being screwed into the combining tubes *k* and provided with washers *o* so that by varying the thickness of the washers the size of the annular jets *m* and consequently the amount of water passing therethrough may be adjusted. In this arrangement as in the previous arrangement described with reference to Figs. 1 and 2, the receiver *h* of the water jet ejector may be connected to a steam jet device *t* for the purpose hereinbefore referred to.

Fig. 6 is a modification of the apparatus shown in Fig. 4, the combining tubes *k* and annular water jets *m* delivering into independent discharge pipes *n'*.

In all cases there may be means for controlling the water supply to any part of the apparatus, as for example, to each of the jets or groups of jets in the receiver or to the annular jet or annular jets arranged in advance of the combining tubes leading therefrom.

The water jet ejectors described may be used in connection with steam condensers of any type, for example, they may be used in connection with surface condensers from which the aerated vapor alone or together with the water of condensation passes into the receiver of the ejector either directly or by means of a steam jet; they may be used in connection with jet condensers in which the aerated vapor passes into the receiver of the ejector, the water of condensation being withdrawn by other means; they may be used as a water jet ejector condenser in which all the steam flows into and is condensed in the receiver, or they may be used

for withdrawing air or gas in any connection and for any purpose, the design being varied according to requirements.

It has been found that in order to obtain a high vacuum when withdrawing air by water jets in the manner described, the air must first mingle with water spray so as to become entrained with the small particles of water which carry the air into the center jet issuing from the elongated jet tube. It will be seen from the illustration that the jets *g* are small and so formed as to produce a shower or spray, while the jet *f* is large and acts to force the shower or spray into the combining tube *k* from which the water is ejected by the annular jet *m*. If a large jet *f* alone were used, or if multiple large jets *f* were employed, not only would the consumption of ejecting water be very great and therefore the power required to work the apparatus unnecessarily large, but the efficiency of the apparatus would be very low as the air entraining effect of the surface of the high velocity jets would only be small, whereas by my arrangement the small jets *g* produce a shower which in falling through the air absorbs it and carries it into the large jets issuing from the elongated nozzles *f*.

When a steam jet is employed in combination with the water jets, the shower or spray of water issuing from the jets *g* condenses the steam from the steam jet and carries the aerated particles of water into the central water jet *f* by which they are discharged.

What I claim is:—

1. A water jet ejector comprising a receiver having a plurality of groups of jets, each group consisting of an elongated jet tube surrounded by a series of short jets, and a separate combining tube for each group of jets, substantially as described.

2. A water jet ejector comprising a receiver containing multiple water jets arranged in groups, each group of jets delivering into a separate combining tube which is surrounded by an annular water jet, each combining tube and annular water jet delivering into a discharge pipe.

3. A water jet ejector comprising a receiver containing multiple water jets arranged in groups, each group of jets delivering into a separate combining tube having one or more water jets in advance thereof.

4. A water jet ejector comprising a receiver containing multiple water jets arranged in groups, each group of jets delivering into a separate combining tube having an annular water jet in advance thereof, said combining tubes converging into one common discharge pipe.

5. A water ejector comprising a receiver containing multiple water jets arranged in groups, each group of jets delivering into a

- separate combining tube having an annular water jet in advance thereof, said combining tubes and annular jet converging into one common discharge pipe.
5. 6. A water jet ejector comprising a receiver containing several groups of water jets, each group comprising a central water jet and multiple smaller water jets, said central jet and multiple smaller jets in each 10 group discharging into a separate combining tube leading from the receiver, each combining tube having an annular water jet in advance thereof, said combining tubes and annular water jets converging into one common discharge pipe.
7. An ejector comprising a steam jet ejecting device and a multiple water jet device having a receiver into which said steam jet discharges, said receiver containing multiple water jets arranged in groups, each group of jets delivering into a separate combining tube, said combining tubes converging into one common discharge pipe.
8. An ejector comprising a steam jet 25 ejecting device and a multiple water jet device having a receiver into which said steam jet discharges, said receiver containing multiple water jets arranged in groups, each group of jets delivering into a separate combining tube having one or more annular water jets in advance thereof.
9. An ejector comprising a steam jet ejecting device and a multiple water jet device having a receiver into which said steam 30 jet discharges, said receiver containing multiple water jets arranged in groups, each group of jets delivering into a separate combining tube having an annular water jet in advance thereof, each combining tube 35 and annular water jet delivering into a discharge pipe.
10. A water jet ejector comprising a receiver containing multiple water jets arranged in groups, each group of jets delivering into a separate combining tube, said combining tubes converging into one common discharge pipe, each combining tube having an annular water jet in advance thereof, and means for controlling the water 45 supply to each group of water jets and means for controlling the supply to the annular jets in said receiver.
11. A water jet ejector comprising a receiver containing water jets, separate combining tubes for the discharge of fluid from the receiver, an annular water jet in advance of each combining tube and means for controlling the water supply to said water jet in advance of each combining tube.
12. A water jet ejector comprising a receiver containing multiple water jets arranged in groups, each group of jets delivering into a separate combining tube having an annular jet in advance thereof, the supply 55 of water to each group of water jets in said receiver and the supply of water to the annular jet in advance of each said combining tube being separately controlled.
13. The combination with a steam condenser of a water jet ejector comprising a receiver containing multiple water jets arranged in groups, whereby air and vapor from the condenser passing into the receiver of said ejector is discharged therefrom by the water jets, each group of jets in said receiver delivering into a separate combining tube having a water jet in advance thereof.
14. The combination with a steam condenser of a water jet ejector comprising a receiver containing multiple water jets arranged in groups, whereby air and vapor from the condenser passing into the receiver of said ejector is discharged therefrom by the water jets, each group of jets in said receiver delivering into a separate combining tube having an annular water jet in advance thereof, said combining tubes and annular water jets converging into one common discharge pipe.
15. The combination with a steam condenser of an air and vapor outlet pipe provided with a steam jet device, and a water jet ejector comprising a receiver containing multiple water jets arranged in groups, said receiver being connected to said condenser by said air and vapor outlet pipe, whereby air and vapor from the condenser is discharged by the steam jet device into the receiver of the ejector, each group of jets in said receiver delivering into a separate combining tube, said combining tubes converging into one common discharge pipe.
16. The combination with a steam condenser of an air and vapor outlet pipe provided with a steam jet device, and a water jet ejector comprising a receiver containing multiple water jets arranged in groups, said receiver being connected to said condenser by said air and vapor outlet pipe, whereby air and vapor from the condenser is discharged by the steam jet device into the receiver of the ejector, each group of jets in said receiver delivering into a separate combining tube having a water jet in advance thereof.
17. A water jet ejector comprising a casting consisting of an upper section, a middle section, and a lower section, said upper section containing nozzles and the water supply thereto, said middle section containing combining tubes into which said nozzles discharge, and said lower section forming with said middle section annular water jets in advance of the combining tubes and which eject the fluid therefrom through a discharge pipe or pipes formed in said lower section.
18. An ejector comprising a steam jet ejecting device and a multiple water jet de- 130

vice into which said steam jet discharges, the multiple water jet device consisting of an upper section, a middle section, and a lower section, said upper section containing several groups of water jets supplied from an annular water passage externally arranged, each group comprising a central water jet and multiple smaller water jets, said middle section containing separate combining tubes into which each group of water jets separately discharge, and said lower section forming with the middle section a water supply chamber and with the

combining tubes in said middle section an annular water jet in advance of each combining tube for the purpose of ejecting the fluid therefrom and delivering through a discharge pipe or pipes also formed in said lower section. 15

Signed at West Hartlepool in the county 20 of Durham, England, this 12th day of March 1912.

DONALD BARNS MORISON.
